Typical inert solvents which can be used with the peracetic acid in this invention include acetone, ethyl acetate, butyl acetate, and dibutyl ether, among others. A method of preparation of peracetic acid is discussed in U.S. Patent No. 2,804,473.

Starting materials which can be readily employed and the resulting aliphatic chloroepoxides in accordance with this invention include:

Starting Materials	Resulting Product
3-chloro-1-propene	3-chloro-1,2-epoxypropane.
3-chloro-1-butene	3-chloro-1,2-epoxybutane.
1-chloro-2-butene	1-chloro-2,3-epoxybutane.
3,4-dichloro-1-butene	3,4-dichloro-1,2-epoxybutane.
1,4-dichloro-2-butene	1,4-dichloro-2,3-epoxybutane.
1-chloro-2-pentene	1-chloro-2,3-epoxypentane.
4-chloro-2-pentene	4-chloro-2,3-epoxypentane.
3-chloro-1-pentene	3-chloro-1,2-epoxypentane.
1,4-dichloro-2-pentene	1,4-dichloro-2,3-epoxypentane.
1-chloro-2-hexene	1-chloro-2,3-epoxyhexane.
1,4-dichloro-2-hexene	1,4-dichloro-2,3-epoxyhexane.
2-chloro-3-hexene	2-chloro-3,4-epoxyhexane.
2,5-dichloro-3-hexene	2,5-dichloro-3,4-epoxyhexane.
4-chloro-2-hexene	4-chloro-2,3-epoxyhexane.
1-chloro-2-heptene	1-chloro-2,3-epoxyheptane.
1,4-dichloro-2-heptene	1,4-dichloro-2,3-epoxyheptane.
4-chloro-2-heptene	4-chloro-2,3-epoxyheptane.
2-chloro-3-heptene	2-chloro-3,4-epoxyheptane.
5-chloro-3-heptene	5-chloro-3,4-epoxyheptane.
2,5-dichloro-3-heptene	2,5-dichloro-3,4-epoxyheptane.
1-chloro-2-octene	1-chloro-2,3-epoxyoctane.
4-chloro-2-octene	4-chloro-2,3-epoxyoctane.
1,4-dichloro-2-octene	1,4-dichloro-2,3-epoxyoctane.
2-ethyl-2-hexenyl chloride	2-epoxy-2-ethylhexyl chloride.
3-chloro-4-octene	3-chloro-4-epoxyoctane.
2,5-dichloro-4-octene	2,5-dichloro-4-epoxyoctane.
2,5-dichloro-3-octene	2,5-dichloro-3,4-epoxyoctane.
5-chloro-3-octene	5-chloro-3,4-epoxyoctane.
2-chloro-3-octene	2-chloro-3,4-epoxyoctane.
1-chloro-2-nonene	1-chloro-2,3-epoxynonane.
4-chloro-2-nonene	4-chloro-2,3-epoxynonane.
1,4-dichloro-2-nonene	1,4-dichloro-2,3-epoxynonane.
2-chloro-3-nonene	2-chloro-3,4-epoxynonane.
5-chloro-3-nonene	5-chloro-3,4-epoxynonane.
2,5-dichloro-3-nonene	2,5-dichloro-3,4-epoxynonane.
3-chloro-4-nonene	3-chloro-4-epoxynonane.
6-chloro-4-nonene	6-chloro-4-epoxynonane.
3,6-dichloro-4-nonene	3,6-dichloro-4-epoxynonane.
1-chloro-2-decene	1-chloro-2,3-epoxydecane.
4-chloro-2-decene	4-chloro-2,3-epoxydecane.
1,4-dichloro-2-decene	1,4-dichloro-2,3-epoxydecane.
2-chloro-3-decene	2-chloro-3,4-epoxydecane.
5-chloro-3-decene	5-chloro-3,4-epoxydecane.
2,5-dichloro-3-decene	2,5-dichloro-3,4-epoxydecane.
3-chloro-4-decene	3-chloro-4,5-epoxydecane.
6-chloro-4-decene	6-chloro-4,5-epoxydecane.
3,6-dichloro-4-decene	3,6-dichloro-4,5-epoxydecane.
4-chloro-5-decene	4-chloro-5,6-epoxydecane.
4,7-dichloro-5-decene	4,7-dichloro-5,6-epoxydecane.

The analysis for the epoxide group is based upon its reaction with pyridine hydrochloride to form the chlorohydrin and pyridine. Into a pressure bottle containing 25 milliliters of 1 N pyridine hydrochloride in chloroform was introduced a sample of epoxide calculated to use about 50 percent of the pyridine hydrochloride. The bottle was then closed and the contents heated in a steam bath for a period of one hour. At the end of that time the bottle and contents were cooled, 10 drops of phenolphthalein indicator (1.0 gram per 100 milliliters of 60 percent ethanol) added, and the mixture titrated to a permanent red endpoint with standard 0.2 N alcoholic potassium hydroxide solution. A blank was also run in precisely the same fashion except that the sample was omitted.

A distinct advantage of the process of this invention is the production of epichlorohydrin of high purity and in high yield in a single-step process which permits a convenient continuous operation. The present commercial process for the production of epichlorohydrin, mentioned hereinbefore, is an example of the well known halohydrin route which involves the addition of hypochlorous acid to allyl chloride and subsequent dehydrohalogenation with sodium hydroxide to produce epichlorohydrin, salt and water. This commercial process suffers from the serious economic disadvantage that it requires the consumption of one mol of hypochlorous acid and one mol of base to produce epichlorohydrin from allyl chloride.

Additionally, there is also the recovery or waste prob-

lem of the co-product sodium chloride. Furthermore, problems of corrosion are encountered in handling aqueous sodium chloride, and the use of special, more expensive, equipment is necessary to avoid this corrosion.

5 An advantage of the process of this invention is the production of a single product of known structure. Frequently the halohydrin route fails to yield a pure compound. This problem is especially true when one attempts to prepare the epoxide of dihaloalkene. For example, the addition of hypochlorous acid to 1,4-dichloro-2-butene yields a compound:

10 15 which on dehydrohalogenation with base gives a mixture of:

20 and

25 The problem is also encountered with many monohalo-alkenes such as, for example, crotyl chloride. Addition of hypochlorous acid to crotyl chloride gives a mixture of:

30 35 and

35 which on dehydrohalogenation with base yields a mixture of:

40 The synthesis of epichlorohydrin mentioned hereinbefore is one of the few cases where a single product is obtained since when either chlorine atom of glycerol dichlorohydrin is removed by dehydrohalogenation the same product results.

45 50 The present application is a continuation-in-part of our copending application Serial No. 439,878, filed June 28, 1954, now abandoned.

The following examples serve to illustrate the practice of the invention.

EXAMPLE I

Preparation of Chloroisobutylene Oxide From Methallyl Chloride and Peracetic Acid

55 Methallyl chloride (533 grams) containing 0.2 percent of pyrogallol inhibitor was heated under reflux at atmospheric pressure (kettle temperature 72° C.) in a kettle equipped with a 3-foot column packed with glass helices. Over a period of 2 hours and 20 minutes, 502 grams of a 30.2 percent solution of peracetic acid in acetone was added to the kettle. The kettle temperature remained at 72° C. throughout the addition. After an additional 2.5-hour reaction period the reaction mixture was allowed to stand overnight at room temperature. The reaction mixture was then fractionally distilled. A 70 percent yield of chloroisobutylene oxide was obtained in a cut boiling at 40° C. to 50° C. at 50 mm. pressure which contained about equal weights of acetic acid and the oxide. A portion of this mixture was steam distilled under 260 mm. pressure. The chloroisobutylene oxide came over at 58° C. and separated out as a lower layer which was continuously removed. After drying, the oil layer (n_{D}^{20} 1.4280) analyzed 99.5 percent as chloroisobutylene oxide,

using pyridine hydrochloride in chloroform as the analytical reagent.

EXAMPLE II

Preparation of 3-Chloro-1,2-Epoxybutane From 3-Chloro-1-Butene and Peracetic Acid

A solution of peracetic acid (1460 grams of a 20.7 percent solution) in acetone was added dropwise over a period of 4 hours to 1448 grams of 3-chloro-1-butene containing 2.8 grams of trinitrobenzene as an inhibitor. The temperature was maintained at 58° C. to 60° C. throughout the addition. An additional 8-hour reaction period at this same temperature was required before the peracetic acid was substantially all reacted (91 percent). The reaction mixture was stripped of excess chloroalkene and acetone under reduced pressure. The residue was diluted with 500 grams of carbon tetrachloride and washed three times with water to remove acetic acid. The washed oil layer was then distilled under reduced pressure. The cuts boiling between 45° C. and 50° C. at 50 mm. pressure had a purity of 90.5 percent as judged by an analysis for epoxide by the pyridine-hydrochloride in chloroform method. Distillation of the water wash material gave additional epoxide. The combined yield, based on peracetic acid, was 68 percent of the theoretical.

EXAMPLE III

Preparation of 1,4-Dichloro-2,3-Epoxybutane From 1,4-Dichloro-2-Butene and Peracetic Acid

A solution of peracetic acid in acetone (78 grams of a 21.5 percent solution) was fed dropwise with stirring to a flask containing 1000 grams of 1,4-dichloro-2-butene at 60° C. After adding approximately one-half of the peracetic acid, an analysis indicated that the reaction was proceeding slowly. The temperature was raised to 80° C. to 88° C. and the addition continued. A total of 4 hours was required for the addition to be completed. The reaction was continued for an additional 2 hours at 80° C. to 88° C. After standing overnight at room temperature the reaction mixture was fractionally distilled. The product, 1,4-dichloro-2,3-epoxybutane, had the following properties:

$$n_{D}^{20} = 1.4743$$

$$\text{Sp. grav. } 30^{\circ} \text{ C.} = 1.3112$$

15

	Calc.	Found
Molecular refraction	30.55	30.20
Oxygen analysis, percent	11.35	11.64; 11.70
Epoxide analysis (morpholine method), percent	100	98.5

EXAMPLE IV

Preparation of Epichlorohydrin From Allyl Chloride and Peracetic Acid

A solution (256 grams) of peracetic acid (32.7 percent) in acetone containing 0.5 gram of sodium pyrophosphate was added dropwise over a period of 1 hour to a kettle of boiling allyl chloride (430 grams). The reaction mixture was heated under reflux (temperature 50° C. to 53° C.) for an additional 6 hours, at which time an analysis for peracetic acid indicated that 89 percent of it had reacted. The excess allyl chloride and acetone were removed from the reaction mixture by distillation at 170 mm. pressure. The pressure was reduced and the product, epichlorohydrin, was distilled as a mixture with acetic acid. The epichlorohydrin and acetic acid were separated by steam distillation under reduced pressure (120 mm.). The lower layer was removed continuously from the distillate, dried over sodium sulfate, and distilled on a Vigreux column to give a 50 percent yield of epichlorohydrin having a boiling point of 52° C. at 74 mm. pressure.

EXAMPLE V

Preparation of Epichlorohydrin

A method of analysis for epichlorohydrin in the presence of acetic acid and allyl chloride was developed and checked against synthetic mixtures. The method involved the reaction of pyridinium chloride in chloroform solution with epichlorohydrin with a correction made for the acetic acid present. This method gave accurate values for known compositions of acetic acid, epichlorohydrin, and allyl chloride.

A series of runs was made in a stainless steel bomb to check the effect of a sequestering agent and various inhibitors on the reaction between peracetic acid and allyl chloride. At the end of the reaction the reaction mixtures were distilled and were analyzed by the above method. This gave an accurate value of the yield of epichlorohydrin. The losses and the time involved in separating epichlorohydrin from acetic acid on a small scale were thus eliminated. In each of these runs the molar ratio of allyl chloride to peracetic acid was 5 to 1, and the reaction temperature was 60° C. The sequestering agent was $\text{Na}_5(2\text{-ethylhexyl})_5(\text{P}_3\text{O}_{10})_2$, "Victawet 35B." A summary of these runs is given in the following table:

Run No.	Reaction time, hours	Sequestering agent, percent	Inhibitor	Yield of epichlorohydrin, percent
30	7.5	0.05	None	66
	7.0	0.1	None	76
	10.0	0.1	0.1% trinitrobenzene	84.1
	8.0	0.1	0.1% 2,4-dinitro-6-chloro-phenol	84.9
	9.0	0.1	0.1% 2-nitro-4-chloro-aniline	65
	8.5	0.1	0.1% phenyl-beta naphthyl-amine	61

EXAMPLE VI

Continuous Preparation of Epichlorohydrin at 100° C.

Epichlorohydrin was prepared continuously by passage of a mixture of allyl chloride and peracetic acid solution through a stainless steel coil under pressure and heated to 100° C. with steam. The following charge stock was made up:

Allyl chloride	grams	530
35% solution of Victawet 35B in acetic acid	cc	0.95
Peracetic acid solution in acetone		

(24.7%) grams 451

and put under 75 pounds per square inch nitrogen pressure and passed through a coil made of $\frac{1}{8}$ -inch stainless steel tubing having a volume of 67 cc. The tube effluent was analyzed for peracetic acid and for epichlorohydrin as described in Example V. The results are recorded in the following table:

Run No.	Temp., °C.	Pressure, p.s.i.	Feed contact		Peracetic acid consumed, percent	Yield of epichlorohydrin, percent
			Rate, cc./hr.	Time, minutes		
(1)	100	75	230	17.4	89	81.5
	100	75	110	36.5	96.2	86

EXAMPLE VII

Preparation of 3,4-Dichloro-1,2-Epoxybutane

Twenty mols (2500 grams) of 3,4-dichloro-1-butene was placed in a 3-necked, 5-liter flask equipped with a stirrer, thermometer, and dropping funnel. A weight of 2.5 grams (0.1% by weight of the olefin) of

"Victawet 35B," was added as a stabilizer. Then, with stirring at 75°, 5 mols of 25.0 percent peracetic acid in ace-

tone was added over a 3-hour period. After heating for an additional 1.5 hours, analysis for peracetic acid showed that a conversion of 89 percent had been achieved.

The reaction mixture was charged to a distillation kettle attached to a packed 24-inch glass column. Then at 50°, the acetic acid and acetone were removed by flash distillation. It was observed that the last amounts of acetic acid distilled as an azeotrope with unreacted 3,4-dichloro-1-butene. The remaining material was carefully fractionated to obtain pure unreacted olefin and the desired epoxide. A total of 471 grams (75 percent) of 3,4-dichloro-1,2-epoxybutane was obtained. The epoxide distilled at 43° at 2 mm. pressure. An index of refraction of $n_D^{30}=1.4740$ was observed for this compound. An analysis for epoxide by the "pyridine hydrochloride in chloroform" method indicated a purity of 93.3 percent. However, no foreign groups such as olefin, carbonyl, or hydroxyl were found to be present by an examination of the infrared absorption spectrum. Redistillation gave material of the same physical properties, indicative of the presence of a single compound.

EXAMPLE VIII

Preparation of 2,3-Epoxy-2-Ethylhexyl Chloride

(a) PREPARATION OF THE UNSATURATED HALIDE

To a mixture of 256 grams of 2-ethyl-2-hexenol and 167 grams of pyridine was added, over a period of 2.3 hours, 319 grams of thionyl chloride at a temperature of approximately 0° C. The reaction mixture was then held at 5° C. for 1 hour and then heated to 70° C. for an additional 3 hours. The reaction mixture was cooled, diluted with 600 cc. of hexane, and poured into 1500 grams of ice and water with vigorous agitation. The organic layer was separated and washed twice with dilute sodium carbonate solution. Distillation gave a 49 percent yield of 2-ethyl-2-hexenyl-chloride having a boiling point of 52° C. to 54° C. at 10 mm. pressure and a refractive index range of 1.4449-1.4485 (n_D^{30}). The refractive index range is probably due to the product's being a mixture of cis and trans isomers. Analysis for allylic chlorine by saponification and determination of chloride ion by the Volhard method indicated a purity of 92 percent. Quantitative bromination analysis indicated a purity of 96 percent.

(b) PREPARATION OF THE EPOXIDE

A solution of peracetic acid in acetone (390 grams of a 22 percent solution) was added over a period of 1.5 hours to 110 grams of 2-ethyl-2-hexenyl chloride at a temperature of 40° C. The temperature was raised to 50° C. and the reaction allowed to continue for an additional 4 hours. Toluene (300 cc.) was added, and the acetone was removed by distillation under reduced pressure. The residue was washed with water to remove acetic acid and then fractionated under reduced pressure. A 57 percent yield of 2,3-epoxy-2-ethylhexyl chloride, a colorless liquid boiling at 70° C. to 71° C. at 10 mm. pressure and having a refractive index of 1.4420 (n_D^{30}) was obtained. An analysis by the pyridinium-chloride-in-chloroform method for epoxide indicated a purity of 94 percent.

EXAMPLE IX

Preparation of 2-Chlorooctenes

According to the teachings of Prileschajew (Berichte 59B, 194-198 (1926)), 458 grams of phosphorus pentachloride was added dropwise over a 2-hour period to 250.4 grams of n-hexyl methyl ketone with stirring. The temperature was maintained in the 0° C. to 10° C. range by cooling the flask with a Dry Ice-acetone bath. After an additional 2-hour reaction period at 10 to 12° C. the reaction mixture was added dropwise over a 1.5-hour period to a solution of 600 grams of sodium hydroxide in 2 liters of water. The neutralized mixture was filtered to

remove the salt and the layers were separated. Distillation of the oil layer gave 78 grams (27 percent yield) of 2-chlorooctenes boiling at 83-85° C. at 50 millimeters and having a refractive index range of 1.4356-1.4366 (n_D^{30}). Examination of the infrared spectrum (bands at 6.08 and 6.2 μ and at 11.4 and 12.35 μ) of this product indicated that it was a mixture of 2-chloro-1-octene and 2-chloro-2-octene.

EXAMPLE X

Reaction of Peracetic Acid With 2-Chlorooctenes

To 95 grams of the 2-chloro-2(1)-octene mixture above, was added 224 grams of a 25.4 percent solution of peracetic acid in ethyl acetate. The temperature was maintained at room temperature for 17 days under conditions which were analogous to the teachings of Prileschajew (Berichte 59B, 194-198 (1926)). The products were isolated by distillation after first azeotroping the volatiles with ethylbenzene. Approximately 24 grams of reaction product was obtained. Infrared analysis indicated a mixture of epoxide and chloroketone, with the chloroketone predominating.

What is claimed is:

1. A process which comprises contacting a chloroolefin compound of the formula:

wherein R_1 , R_2 , R_3 , R_4 , and R_5 are selected from the group consisting of hydrogen, alkyl, and chloroalkyl, said chloroolefin compound containing from 3 to 10 carbon atoms and a maximum of two chlorine atoms in allylic positions; with peracetic acid, under anhydrous conditions, at a temperature in the range of from about 40° C. to about 150° C., for a period of time sufficient to produce the corresponding monoepoxide.

2. The process of claim 1 wherein the reaction is carried out at a temperature in the range of from about 40° C. to about 130° C.

3. The process for the production of 3-chloro-1,2-epoxybutane which comprises contacting 3-chloro-1-butene with peracetic acid, under anhydrous conditions, at a temperature in the range of from about 40° C. to about 130° C., for a period of time sufficient to produce 3-chloro-1,2-epoxybutane.

4. The process for the production of 1,4-dichloro-2,3-epoxybutane which comprises contacting 1,4-dichloro-2-butene with peracetic acid, under anhydrous conditions, at a temperature in the range of from about 40° C. to about 130° C., for a period of time sufficient to produce 1,4-dichloro-2,3-epoxybutane.

5. The process for the production of epichlorohydrin which comprises contacting allyl chloride with peracetic acid, under anhydrous conditions, at a temperature in the range of from about 40° C. to about 130° C., for a period of time sufficient to produce epichlorohydrin.

6. The process for the production of 3,4-dichloro-1,2-epoxybutane which comprises contacting 3,4-dichloro-1-butene with peracetic acid, under anhydrous conditions, at a temperature in the range of from about 40° C. to about 130° C., for a period of time sufficient to produce 3,4-dichloro-1,2-epoxybutane.

7. The process for the production of 2,3-epoxy-2-ethylhexyl chloride which comprises contacting 2-ethyl-2-hexenyl chloride with peracetic acid, under anhydrous conditions, at a temperature in the range of from about 40° C. to about 130° C., for a period of time sufficient to produce 2,3-epoxy-2-ethylhexyl chloride.
